United States Patent Office

Des. 193,798

Patented Oct. 9, 1962

193,798

PITCHER OR THE LIKE

Patrick E. Tahaney, 1608 Arthur Ave., Orlando, Fla.

Filed Oct. 12, 1961, Ser. No. 67,060

Term of patent 14 years

(Cl. D44—21)

FIG. 1.

FIG. 2.

FIG. 1 is a view in elevation of a pitcher, showing my new design; and

FIG. 2 is a cross-sectional view taken on the line 2—2 of FIG. 1.

The essential figures of my design are shown in full lines on the drawings.

I claim:

The ornamental design for a pitcher or the like, as shown and described.
